UNITED STATES PATENT OFFICE.

ANDREW B. WERIANE, OF DENVER, COLORADO.

MECHANICAL MOVEMENT.

1,324,945.

Specification of Letters Patent. Patented Dec. 16, 1919.

Application filed December 5, 1918. Serial No. 265,461.

To all whom it may concern:

Be it known that I, ANDREW B. WERIANE, a citizen of the United States, residing at Denver, in the county of Denver, and State 5 of Colorado, have invented certain new and useful Improvements in Mechanical Movements; and I do hereby declare the following to be a full, clear, and exact description of the invention, such as will enable others 10 skilled in the art to which it appertains to make and use the same.

This invention relates to mechanical movements and more particularly to an improved planetary gear train or organization.

15 It is one of the objects of the present invention to provide a novel planetary gear train and more particularly it is another object of the present invention to provide improvements in this type of mechanism 20 wherein a master or annular member may be operatively connected to a set of planetary gears which in turn are operatively connected to another set of planetary gears engaging a control or fixed gear whereby 25 the desired movement of the organization and its respective elements may be secured.

With these and other objects in view as will be rendered manifest in the following specification, the invention consists in the 30 construction, the combination, and in details and arrangement of parts to be more particularly set forth hereinafter relative to the embodiment of the invention illustrated in the accompanying drawing, wherein,

35 Figure 1 is a side elevation of the mechanism with one of its shafts being shown in section.

Fig. 2 is a plan view of Fig. 1 showing the shaft broken away.

40 Fig. 3 is a side elevation of the organization taken from the side opposite to that shown in Fig. 1.

Fig. 4 is a plan view of one form of carrier for the planetary gears.

45 Fig. 5 is a view in side elevation, with its shaft broken away showing a modified form of the invention and,

Fig. 6 is a plan view of the same, also showing the shaft broken away.

50 In the form of the organization illustrated in Figs. 1, 2, 3, and 4, there is provided a master gear A, mounted on a shaft 2 which is supported in a journal or bearing 3; the rim of the gear A being provided 55 with a part 4 indicating means for the application of force or power to the wheel.

Intermeshed with the teeth of the internal gear A and disposed at diametrically opposite points thereof is a set of internal pinions or gears 5—5 which are appropriately 60 mounted in the outer ends of radial arms or other suitable carrier 6, mounted on a shaft 7, supported in a bearing 8, which shaft alines with the shaft 2 so that the gears 5 may move in an orbit concentric to 65 the shaft axes 2 and 7. The planetary gears 5—5 are fixed on respective shafts 9 which have secured thereon sprocket pinions 10 over which run respective sprocket chains 11, engaging with sprocket wheels 12, turning 70 about respective axes 13, on the carrier 6. Fixed to the gears 12 for rotation therewith about their respective axes 13 are pinions 14 meshing with an internal fixed gear 15, shown as connected to the bearing 8. From the above description it will be seen that upon a tendency of the rotation of the master wheel A in the direction of its arrow, the planetary gear train will by reason of the engagement of its pinions 14 80 with the fixed gear 15 tend to rotate the arms or carriers 6 in a direction reverse to that of the master internal gear A.

A similar result may be accomplished by the utilization of the modification of the 85 invention which is illustrated in Figs. 5 and 6. In this construction the carrier consists of a disk or plate 16, on which the shafts 9, with planetary gears 5 and their sprocket pinions 10 are mounted and also the pinions 90 14 engaging the fixed internal gear 15 but instead of employing the internal master gear A an endless sprocket chain 18 is utilized to engage the planetary gears 5, this chain being supported on sprockets 19, arranged around the edge of the plate or carrier 16. Therefore power applied to move the chain 18, as for instance, as is indicated 95 by the weight 20, tends to move the planetary mechanism with the carrier 16 in the 100 opposite direction.

In the drawing there is shown and hereinabove there is described the preferable form of this invention, but it will be understood that, without departing from the 105 spirit of the invention, the gears 5 and pinions 14 and the parts forming the operative connection between the gears 5 and pinions 14, may be decreased to one each or increased to any desired number each. Also 110 it will be understood that various changes may be made in the details of construction.

without departing from the spirit of the invention.

What I claim is:

1. A gear organization comprising a fixed gear, a pair of pinions engaging the same; a rotary carrier on which the pinions are mounted, the carrier having an axis alined with that of the fixed gear; outer planetary gears operatively connected to the pinions and also mounted on the carrier to turn therewith about its axis; and an annular member operatively connected to the planetary gears and concentric to the axis of the carrier.
- 15 2. A gear organization comprising a fixed gear, a pair of pinions engaging the same; a rotary carrier on which the pinions are mounted, the carrier having an axis alined with that of the fixed gear; outer planetary gears operatively connected to the pinions and also mounted on the carrier to turn therewith about its axis; and an annular rotary member operatively connected to the planetary gears and turning about concentric to the axis of the carrier.
- 20 3. A gear organization comprising a fixed internal gear, a pair of pinions engaging the same; a rotary carrier on which the pinions are mounted, the carrier having an axis alined with that of the fixed gear; outer planetary gears and a sprocket chain

mechanism operatively connecting the pinions and the planetary gears and also mounted on the carrier to turn therewith about its axis; and an annular member operatively connected to the planetary gears and concentric to the axis of the carrier.

4. A gear organization comprising a fixed orbit gear, pinions engaging the same; a rotary carrier on which the pinions are mounted, the carrier having an axis alined with that of the fixed gear; outer planetary gears and transmitting means for operatively connecting them to the pinions and also mounted on the carrier to turn therewith about its axis; and an internal master gear engaging the planetary gears.

5. A gear organization comprising a fixed orbit gear, a pinion engaging or rolling about the same; a rotary carrier on which the pinion is mounted, the carrier having an axis alined with that of the fixed gear; an outer planetary gear and transmitting means operatively connecting it to the pinion and also mounted on the carrier to turn therewith about its axis; and an annular member operatively connected to the planetary gear and concentric to the axis of the carrier.

In testimony whereof I affix my signature.

ANDREW B. WERIANE.
